UNITED STATES PATENT OFFICE.

WILLIAM E. BIRKET, OF PEORIA, ILLINOIS.

SOUND RECORDING AND REPRODUCING MACHINE.

1,422,022.

Specification of Letters Patent. Patented July 4, 1922.

Application filed March 25, 1921. Serial No. 455,529.

To all whom it may concern:

Be it known that I, WILLIAM E. BIRKET, a citizen of the United States, residing at Peoria, in the county of Peoria and State of Illinois, have invented certain new and useful Improvements in Sound Recording and Reproducing Machines; and I do hereby declare that the following is a full, clear, and exact description of the invention, which 10 will enable others skilled in the art to which it appertains to make and use the same.

My invention relates to sound recording and reproducing machines, having especial reference, however, to certain mechanism in 15 connection with the motor thereof and the socalled "tone-arm" by which to govern the speed of rotation of the turn table upon which the record-disc is carried.

In present day motor-operated machines, 20 the turn table is rotated at a certain definite speed. That is to say, the shaft carrying said table, in one type of machine at least, is driven at the arbitrary speed of 78 revolutions per minute. This shaft speed, or any 25 other speed for that matter, means, therefore, that the record-disc must have the same speed. At the inner end or terminal of the scroll this rate of travel for the disc beneath the stylus is perhaps desirable, but at the 30 margin of the disc the travel beneath such stylus is exceedingly rapid which means, for purposes of comparison, that at said margin or the starting end of the scroll a recorded sound will be very long and two 35 recorded sounds will be very widely spaced from one another whereas at said inner terminus these recorded sounds will be short and lie very close together.

Now, were the impressions at the margins 40 and over the entire intervening surface of the disc as closely placed as at the said inner terminus of the scroll, it is clear that a much longer "record" could be produced in the same length of scroll for any given diameter 45 of disc. And that this may be done, it is necessary that the rate of travel of the disc beneath the stylus be the same at all times without respect to the position of such stylus.

50 The main object of my invention, therefore, is that of providing mechanism for so controlling the motor, whatever its type, that the speed of travel of the disc beneath

the stylus will be the same at all positions of the latter between the beginning of the scroll 55 and the terminus thereof, both in a recording and reproducing machine.

Another object is that of interposing mechanism between the "tone-arm" and the governing means for the motor, so controlled 60 during the swing of the former that the speed of rotation of the disc will be gradually increased as the stylus moves inwardly from the start of the scroll to the inner terminus of the same, the disc, as the said 65 terminus is reached, then rotating at the speed usually required for recording or reproducing at that point.

In order to accomplish the result stated, 70 the rate of travel of the disc must be such, due to the constantly changing distance of travel thereof in each rotation beneath the stylus, i. e., an ever decreasing circumference, as the stylus moves toward the center 75 of rotation, the driving mechanism, of what ever type, must be governed in accordance.

For example, a disc twelve inches in diameter in order to have a rate of say 78 rotations per minute, must, at the outer end of the scroll, have 26 rotations when the stylus 80 is at the start of the scroll due to the very much greater distance of travel at the point beneath the stylus in order that the recorded sounds and spacing of sounds may be the same as those at said inner end of said 85 scroll. Now, since the stylus bears a direct relation to the "scroll circumference" during disc rotation, the "tone-arm" carrying said stylus is the controlling factor together with the power that rotates the disc. Therefore, 90 the introduction of a suitable mechanism between the "tone-arm" and the power will provide for the desired control of such disc rotation in either the recording or reproducing machine, being fully aware that 95 it is not new to change the speed of rotation of a disc with respect to a stylus while moving the center of rotation of the disc by a hand-feed device.

I am also aware of a special type of machine involving a special arrangement of motor setting and friction device for the disc which is ever changing during disc rotation to obtain the same increased speed as the inner terminus of the scroll is approached. 105 My device, however, is designed to require

no change in the prevalent types of machines, being an attachment for the same.

In the accompanying drawing,

5 Figure 1 is a plan of a conventional type of sound reproducing machine,

Figure 2 is a sectional elevation of part of the same on a larger scale taken on line 2-2, Figure 1,

10 Figure 3 is a cross section of a tone-arm and a cam attached thereto,

Figure 4 is an elevation similar to Figure 2 in which the parts are produced on a larger scale,

15 Figure 5 is a plan of certain mechanism shown in the previous figures, and

Figure 6 is a transverse section, in elevation, of a part shown both in Figure 5 and some of the other figures.

20 1 indicates, in this case, the cabinet of a reproducing machine, 2 the turn-table, 3 the shaft or spindle carrying it, 4 a record-disk, and 5 the usual tone-arm with its sound box.

25 6 represents the motor for operating the turn-table, which may be of any desired type, being shown herein as a spring motor including the usual governor and friction disc 7 for controlling it.

30 An adjustable part, not shown, is usually employed for governing the rate of rotation of the turn-table through a link 8 connected with a pivotally hung bell-crank 9, Figures 2 and 4, adapted to engage the friction disc 7 by a button of felt or other material 10. Thus far I have described sound reproducing machine as usually built, with any of the forms of which my invention, now to be described, may be readily used.

35 11 is a lever fulcrumed at any convenient point upon or beneath the deck of the cabinet. For convenience in the present instance, it is shown pivoted beneath the turn-table at 12, for example, one end having attachment to the link 8, its other end having an arm 13 pivotally mounted thereon adapted to be adjusted with respect to said lever by means of a screw 15 at each side of the fulcrum at 14, for example.

40 16 is a thumb-screw carried by the arm adapted at times to rest upon an anvil 17 on the deck of the cabinet as will appear later.

45 The arm has a downturned extension 18 at its free end designed to engage a cam 19 mounted upon the tone-arm to turn with the same, said extension preferably having a projection 18' to engage behind the cam for retaining the arm in operative position.

50 For convenience said cam is carried by a band 19' arranged to be clamped upon the said tone-arm as shown in Figure 3. It has an inclined surface 20 upon which the said downturned extension may rest and said incline is of such an extent and form that the lever 11 will be moved between certain limits 55 corresponding to the start and finish of the

record-scroll. Further, the cam preferably has an incline 21 in an opposite direction as shown.

56 In order to more readily understand the operation of the arrangement, 78 will be 70 taken as the figure representing the usual number of revolutions of the turn-table. Now, with the parts arranged as shown in Figure 2, but with the stylus moved outward (not shown) beyond the margin of the 75 disc a sufficient distance to permit the arm 13 to ride down the incline 21 to permit the end of the lever 11 connected to the link 8 to rise sufficiently to remove some of the friction upon the disc 7, the motor is permitted to "speed up."

80 Now as the tone-arm is brought inwardly to the starting position, the incline 20 in the swing of the tone arm having been brought beneath the extension 18, the friction upon the disc 7 is such, as adjusted by the screws 15, that the turn-table will be confined to 26 revolutions per minute for a disc having a 12 inch diameter, this speed having been found correct for that 85 diameter of disc where speed at the innermost end of the scroll is to be 78 revolutions per minute; the cam surface 20 being so formed, with respect to the fulcrum of the lever and the manner of mounting of 90 the parts, that the governor will be permitted to rotate faster and faster at the proper ratio.

95 At about one-fourth the distance of travel of the stylus inward from the starting position, the speed of the disc will be approximately 31 R. P. M. After the stylus has moved half way across the disc, the revolutions become approximately 52 per minute, gradually increasing, until when the stylus 100 has reached an innermost position, the speed has become 78. And if continued farther, the disc may increase steadily at the same rate. Obviously, in using discs having diameters less than 12 inches, the number of 11 rotations when the stylus is at the margin, must always be correct for those diameters.

115 It must also be evident that if the surface 20 has the same form in all cams, recording and reproduction will be identical 11 when the cams are properly set on individual machines, together with the proper adjustment of the arms 13 with respect to the cam so as to produce the same number of revolutions of the turn-table in a given position of 12 the stylus.

120 My invention, besides admitting of much longer records being recorded and reproduced, can be so adapted without change to the reproduction of records of the types made at the present time.

125 That is to say, the lever 11 is so mounted at its fulcrum 12 that it may be shifted laterally sufficiently, as indicated in broken lines in Figure 5, that the extension 18 may 13

be removed from the cam and dropped down whereupon the screw 16 will rest upon the anvil 17 and when properly adjusted and fixed will always be in position to so govern 5 the motor as to admit of the required fixed speed of 78 revolutions of the disc per minute.

Such an arrangement, therefore, admits 10 of recording and reproducing one type of record, the number of rotations constantly increasing with the travel of the stylus, which in the other case the disc may rotate for reproduction at a constant speed for a record of the common type.

15 The mechanism lying between the tone-arm and the bell-crank 9 may be changed in position to fit any machine with such adaptations that may be necessary. Furthermore, it may be otherwise constructed to accomplish 20 the desired result, the form shown being but one of the types found to answer the purpose. Again, the mechanism is not confined alone to governing motors of the spring operated type, since suitable ways of 25 affecting changes in the speed of other types may be readily provided.

A further advantage in governing the speed of disc rotation may be understood when it is remembered that the greater the 30 speed beneath the stylus the more "scratch" is in evidence and as the stylus approaches the center of rotation, the scratching diminishes. Now, by having a greatly reduced speed, as the starting speed, with a gradual 35 increase to properly reproduce, there will be no more of this undesirable noise at one place than another. Stated in another way, with but a minimum of noise at the finish of the scroll there will be as little at the 40 outer margin of the disc. There are no long blank spaces between the recorded sounds.

The screw 16 virtually corresponds to that commonly used and its adjustment 45 through the lever 11 produces the same result in the control of the governor and when permanently set after the proper speed of rotation of the turn-table is found, the machine is always ready to reproduce from either type of record. Said screw 16 may 50 be placed elsewhere, of course, so long as it has control of the movement of the bell-crank 9.

Clearly, modifications of the parts of the arrangement shown are possible without departing 55 from the spirit and intent of the invention and such as may fall within the scope of the claims, the particular structure shown being but one of the forms that will furnish the desired results.

60 I claim:

1. In combination with the tone-arm and governing means of a sound recording and reproducing machine, mechanism interposed between the said tone-arm and governing 65 means directly engaging both adapted in

the movement of the tone-arm to control the action of said governing means.

2. In combination, with the tone-arm and motor governing means, a cam operated by 70 said arm, and mechanism interposed between the cam and the said means, engaging both, adapted in the movement of the arm to control the said means and the rate of rotation of the motor.

3. In combination with the tone-arm and 75 motor governing means in a machine for producing sound, a cam moved by the arm, and mechanism interposed between the cam and said means, engaging both, adapted in the movement of the arm to govern the 80 speed of the motor through said means.

4. In combination with a record-disc, a tone-arm and its stylus, and power means including a governor, a part constantly changing in position in the travel of the 85 arm with respect to the disc, of mechanism disposed between the part and the said governor to control the latter adapted therethrough to affect a constantly increasing speed rotation of the disc as the stylus moves 90 from the outer to the inner terminus of the disc scroll.

5. In combination with the tone-arm and governing means for the motor of a machine of the class named, a cam moved by said 95 arm, a lever mounted between its ends engaging at one end the cam and at its other engaging said means.

6. In a machine of the type named, a cam mounted on the pivoted end of the tone-arm thereof, a lever fulcrumed between its ends engaging at one end the governor control mechanism, and a part carried by the other end, means to adjust said part to various positions relatively to said lever 100 and fixed in position thereon, the said part 105 adapted to engage said cam.

7. In a machine of the type named, the combination with the tone-arm and governor control means thereof, a cam operated by 110 the said arm, and mechanism engaging both the cam and said control means adapted to be shifted in position relatively to said cam to permit its removal therefrom.

8. In a machine of the type named, the 115 combination with the tone-arm and governor control means thereof, a cam operated by the said arm, mechanism engaging both the cam and said control means adapted to be shifted in position relatively to 120 said cam to permit its removal therefrom, a support for the said mechanism, and means adjustable relatively to said mechanism engaging said support.

9. In combination with the tone-arm and 125 governor control means in a machine of the type named, a moving part operated by the tone-arm in its movement, a lever fulcrumed on the machine extending between the said part and said governing means having en- 130

gagement at one end with the latter and also adapted to be engaged with the said part and movable laterally on its fulcrum arranged and adapted when engaging the part 5 to permit the turntable of the machine to rotate at a constantly increasing speed, and when removed therefrom to cause said turntable to rotate at a constant speed.

10. The combination with the tone arm, motor, and motor governing means in a sound recording and reproducing machine, of a part movable with the said tone arm, and mechanism operatively connected with the said governing means and lying in the 15 path of movement of said part adapted to be operated by the latter in its movement to cause the motor to gradually increase in its rate of rotation, said mechanism adapted to be moved into and out of said path of 20 said part.

11. The combination with the tone arm, motor, and motor governing means in a sound recording and reproducing machine, of a part movable with said tone arm, and

mechanism fulcrumed on the machine oper- 25 atively connected at one end with the governing means and lying in the path of said part adapted at its other end to be operated by said part in the movement of the arm to cause the motor to be gradually released 30 to gradually increase in speed of rotation, said mechanism adapted to be moved out of said path of said part.

12. The combination with the tone arm, 35 motor, and motor governing means in a ma- chine of the class described, of a part mov- able with said tone arm, and mechanism operatively engaging the governing means and said part and mounted whereby it may be moved into and out of the path of the 40 part in its travel.

In testimony whereof I affix my signature in presence of two witnesses.
